UNITED STATES PATENT OFFICE.

HENRY MASBRUCH, OF PLATTEVILLE, WISCONSIN.

ATTACHMENT FOR PUMPS.

Application filed December 31, 1923. Serial No. 683,778.

To all whom it may concern:

Be it known that I, HENRY MASBRUCH, a citizen of the United States, residing at Platteville, in the county of Grant and State 5 of Wisconsin, have invented a new and useful Attachment for Pumps, of which the following is a specification.

The object of my invention is to provide a device which may be readily attached 10 to and adjusted on any hand-operated pump and which will make it easier to operate the pump.

I attain the objects of my invention by the device illustrated in the accompanying drawings, in which:—

Figure 1 is a side elevation of my invention applied to a pump;

Fig. 2 is a front elevation of same; and

Fig. 3 is a perspective view of my attachment removed from the pump.

Like characters of reference designate like parts in each of the several views.

Referring to the accompanying drawings, I provide a bifurcated bracket 2 mounted on 25 the head of the pump 1 and having a depending vertical bracket end 4 to which the ends of a U-bolt or clamping yoke 3, which encircles the pump, may be attached. I provide a set screw 5 for facilitating the adjustment of the device to pumps of different sizes to which it is capable of being attached. I provide a rear clamping bar 6 engaging under the pump handle and secured to the ends of the bifurcated bracket 30 by bolts 7, as shown in Figs. 1 and 3. Affixed to each of the arms of the bifurcated bracket 2 are hollow posts 8 which are reinforced by suitable braces 9. Adjustably mounted in hollow posts 8 are screws 11 which are adjustably supported by the adjusting nuts 12. Attached to the upper ends of screws 11 is a cross bar 10 which is provided with opposite hooks 13. I also provide a lower cross bar 15 affixed to the 40 pump rod 17 by a U-bolt 16, as shown in Figs. 2 and 3. Cross bar 15 is operatively connected with the hooks 13 of the cross bar 10 by suitable springs 14. The point of attachment of lower cross bar 15 to pump rod 17 is at a point below the engagement of pump handle head 18 on the pump rod. When the pump handle is operated the lower cross bar 15 travels downward with the pump rod 17 and the springs 14 are 50 stretched, the tension from which tends to

throw the pump rod upward again, thus making it much easier to pump.

What I claim is:—

1. In an attachment for pumps, the combination of a bracket, means for attaching the bracket to the pump head, means for adjusting said attaching means to permit of securing the device on pumps of different sizes, standards on the bracket, a cross bar separated from the upper ends of the standards, a second cross bar affixed to the pump rod, and springs operatively connecting the two cross bars, for the purposes described. 60

2. In an attachment for pumps, the combination of a bracket, means for rigidly and 70 adjustably securing the bracket to the pump head, standards on the bracket, a cross bar supported from the upper ends of said standards, said cross bar terminating in hooks, a second cross bar affixed to the pump rod at a position substantially below the 75 first cross bar, and springs operatively connecting the second cross bar with the hooks of the first cross bar, substantially as and for the purposes described. 80

3. In an attachment for pumps, the combination of a bracket, said bracket having a vertically depending end portion, a clamping yoke engaging around the pump and secured to said depending end portion of 85 the bracket, a set screw mounted in said end portion of the bracket and adjustably securing the bracket to the pump, means for attaching the rear portion of the bracket to the pump, hollow standards on the 90 bracket, screws adjustably mounted in the upper ends of said standards, nuts resting on the ends of the standards and adapted to adjust the height of the screws, a cross bar carried by the screws, a lower cross bar 95 affixed to the pump rod in spaced relation to the upper cross bar, and springs operatively connecting the two cross bars.

4. In an attachment for pumps, the combination of a bracket, said bracket having 100 a vertically depending end portion, a clamping yoke engaging around the pump and secured to said depending end portion of the bracket, a set screw mounted in said end portion of the bracket and adjustably securing the bracket to the pump, means for 105 attaching the rear portion of the bracket to the pump, standards on the bracket, a cross bar supported from the upper ends of the standards, a second cross bar affixed to the 110

pump rod, and springs operatively connecting the two cross bars, for the purposes described.

5. In an attachment for pumps, the combination of a bracket, means for rigidly securing the bracket to the pump head, substantially hollow standards on the bracket, screws adjustably mounted in the upper

ends of said standards, nuts resting on the ends of the standards and adapted to adjust the height of the screws, a cross bar carried by the screws, a lower cross bar affixed to the pump rod in spaced relation to the upper cross bar, and springs operatively connecting the two cross bars.

HENRY MASBRUCH.
